FLUORESCENT LIGHTING FIXTURE OR SIMILAR ARTICLE

Joseph J. Ostyn, Rochelle Park, N.J., assignor to Ameri-
can Illuminating Company, Inc., Newark, N.J.

Filed Dec. 22, 1965, Ser. No. 282

Term of patent 14 years

(Cl. D48—23)

FIGURE 1 is a perspective view of a fluorescent lighting fixture or similar article showing my new design;

FIGURE 2 is an enlarged, sectional view taken along the lines 2—2 of FIGURE 1, viewed in the direction of the arrows, with a portion of a lamp tube being shown in broken lines for illustrative purposes only;

FIGURE 3 is an end elevational view thereof, the opposite end having the same appearance;

FIGURE 4 is a top plan view thereof with portions broken away for convenience of illustration;

FIGURE 5 is a side elevational view thereof with portions broken away for convenience of illustration, the opposite side having the same appearance; and

FIGURE 6 is a bottom plan view thereof with portions broken away for convenience of illustration.

I claim:

The ornamental design for a fluorescent lighting fixture or similar article, as shown and described.
